(57) CLAIM

The ornamental design for a handle for cooking utensils, as shown and described.

DESCRIPTION

FIG. 1 is a front elevational view of a handle for cooking utensils showing my new design, the rear elevational view being a mirror image thereof;

FIG. 2 is a side view, taken from the left side of FIG. 1, the right side view being a mirror image thereof;

FIG. 3 is a top plan view thereof;

FIG. 4 is a bottom plan view thereof; and,

FIG. 5 is a perspective view thereof.

The broken line showing a skillet in FIG. 5 is for illustrative purposes only and forms no part of the claimed design.
